UNITED STATES PATENT OFFICE.

P. B. REYNOLDS AND L. C. REYNOLDS, OF PROPHETSTOWN, ILL., ASSIGNEES
TO THEMSELVES AND CLARK G. REYNOLDS, ALL OF SAME PLACE.

IMPROVEMENT IN CULTIVATORS.

Specification forming part of Letters Patent No. 37,789, dated February 24, 1863.

To all whom it may concern:

Be it known that we, P. B. REYNOLDS and L. C. REYNOLDS, of Prophetstown, in the county of Whiteside and State of Illinois, have invented a new and useful Improvement in Corn-Cultivators; and we do hereby declare that the following is a full, clear, and exact description of the same, reference being had to the accompanying drawings, forming part of this specification, in which—

Figure 1 is a perspective view of our corn-cultivator. Fig. 2 is a longitudinal section through one of the beams.

The same letters of reference in the several figures indicate corresponding parts.

The nature of our invention consists in an arrangement of an approximate V-frame swing-tree, draft-rods, adjustable draft-rod bars, perforated adjusting-plates, swiveling cultivator standards or stocks, and bent sustaining-bars, all constructed for operation together, as hereinafter described.

It also consists in the arrangement, upon adjustable beams of the frame, of two or more pairs of perforated adjusting-plates for the purpose of setting the swiveling stocks of cultivator-teeth.

It also consists in the arrangement of the bent sustaining-bars, adjustable side beams, and angular slots of the middle and rear beams.

It also consists in the arrangement of the single-tree under and upon the rear beam, and having its draft-rods run forward through adjustable bars of a front cross-piece.

It also consists in the arrangement of the circular adjusting-plate, square upper end of the cultivator-tooth stock, round portion, and the side beam and sustaining-bar.

To enable others skilled in the art to make and use our invention, we will proceed to describe the same with reference to the drawings.

A B C D E designate the five beams which constitute the frame of the cultivator. These beams are placed together so that they form a figure very closely approximating to the letter V. To the beam A, which is the longest cross-beam, and is at the widest or front end of the frame, the angular side beams, B C, are pivoted, as at *a a*. These beams B C are also connect-

ed, by means of angular slots *b b* and *c c* in the middle cross-beam, D, and end cross-beam, E, and screw-bolts *d d* and *e e*, to the middle cross-beam, D, and rear cross-beam, E, in the manner shown. This mode of connection and slots *s s* in the side beams, B C, admits of the side beams being moved nearer together or farther apart on their pivots *a a*. Under the side beams, B C, bent bars F F are arranged, and their ends extended under the front and rear beams, A E, and attached firmly to the pivots *a a* and screw-bolts *e e*.

Through the beams B C, and also the sustaining-bars F F, round holes *f f'* are cut vertically, and through these holes inclined standards or stocks G G' G² are passed loosely. The termini *t t* of these stocks are made flat or square, while the portions below the same are round. The square upper ends of the stocks G' G² receive upon them semicircular plates H H', said plates being confined in place by pins *g g*, as shown. The plates H H' have lever ends *h h*, and are perforated vertically with a series of small adjusting-holes, *i i*, which are formed on a circle struck from the axis of the stocks G' G². In one or another of these holes, accordingly as an adjustment of the stocks is made, a pin, *j*, is inserted, said pin entering a hole, *k*, formed in the beams B C, as shown.

To the under side of the rear beam, E, a single-tree, I, is pivoted centrally, as at *l*. From the ends of this single-tree draft-rods J J extend forward beyond the front beam, A, and pass loosely through vertical bars or hangers K K, which extend down through a fixed cross-piece, L, of the frame. The hangers have a series of adjusting-holes, *m m*, punched horizontally in them, and through one or another of these holes a pin, *n*, is passed, accordingly as the draft-rods are set. On the front ends of the draft-rods whiffletrees M M are hinged, as usual.

On the front and middle beams of the frame hounds N N are arranged, and between the front ends of the same a tongue, O, is fitted and hung by a king-bolt, so as to only be able to turn on the bolt in a downward direction.

From the middle beam handles P P rise and extend back beyond the rear beam, being supported and braced by a standard, a screw-rod, and bars, as indicated by letters Q R S.

The machine thus constructed is provided with any form of cultivator tooth, shovel, or hoe at the lower ends of its stocks or standards.

In the use of the machine two horses are attached to its tongue and whiffletrees, and the horses walk respectively on opposite sides of a row of corn, or with one row between them and two rows outside of them. Thus the central row is hilled on both sides and the other two rows on one side at each passage across the field.

In case it is desired to set the shovels so that they will turn the soil toward or from the corn, the circle-plates are unpinned, and by their lever ends *h*, the stocks, with shovels attached, are turned or adjusted as desired, and the plates again pinned firmly.

The single-tree by being in rear of all of the shovels allows of long draft-rods being employed, and by having such rods and providing for regulating their draft, as described, the whole series of cultivator teeth or shovels are kept down to the work.

The frame by being sustained by the bent bars *F F* is sufficiently strong for the work and draft brought upon it, and at the same time the stocks are sustained midway of their length, and the side beams, stocks, and bars can be adjusted together.

The separate circular plates answer for converting the machine into a right and left cultivator, or for turning one portion of the shovels so that they throw up soil to the hill of corn, and for turning another portion so that they throw off the soil from the hill of corn.

The angular slots *b c* and the slots *s s* allow the rear portion of the cultivator to be constructed or expanded as necessity may demand.

The shovel-stocks might be passed upon the side of the side beams, *B C*, and confined by clamp-bars.

Our machine answers a most excellent purpose on our Western lands, and saves the services of many hands. Our machine might be mounted upon wheels and a crank-axle and have a seat for a driver. The bar *L* might be removed and the bars *K* be passed down through the front beam, *A*.

What we claim as our invention, and desire to secure by Letters Patent, is—

1. The arrangement, upon adjustable beams *B C*, of two or more pairs of perforated lever-adjusting plates *H h i*, for the purpose of adjusting two or more pairs of shovel-stocks, *G' G² t t*, in the manner and for the purpose described.

2. The arrangement of the bent sustaining-bars *F F*, side beams, *B C*, and slots *b c s s*, in the manner and for the purpose described.

3. The arrangement of the frame *A B C D E*, single-tree *I*, draft-rods *J J*, adjustable hangers *K K*, perforated lever-adjusting plates *H H H H*, swiveling square or flat top standards *G' G²*, bent sustaining-bars *F F*, and slots *b c s*, the whole constructed and operating together in the manner and for the purposes described.
